UNITED STATES PATENT OFFICE.

DANIEL S. WAUGH, OF DENVER, COLORADO, ASSIGNOR TO THE ILER ROCK DRILL MANUFACTURING COMPANY, OF DENVER, COLORADO.

AUTOMATIC FLUID-ACTUATED FEED MECHANISM FOR PERCUSSIVE TOOLS.

No. 897,231.

Specification of Letters Patent. Patented Aug. 25, 1908.

Application filed July 20, 1906. Serial No. 327,019.

To all whom it may concern:

Be it known that I, DANIEL S. WAUGH, a citizen of the United States, residing in the city and county of Denver and State of Colorado, have invented certain new and useful Improvements in Automatic Fluid-Actuated Feed Mechanism for Percussive Tools; and I do declare the following to be a full, clear, and exact description of the invention, such as will enable others skilled in the art to which it appertains to make and use the same, reference being had to the accompanying drawings, and to the letters and figures of reference marked thereon, which form a part 15 of this specification.

My invention relates to fluid actuated mechanism for percussive tools being more especially intended for those of the hammer class, whether of the larger variety usually termed drills or of the small class generally termed tools. By virtue of my improvement the operating fluid for the tool also performs the feeding function whereby the body of the drill is automatically moved forward 20 longitudinally to hold the bit or cutting device in contact with the material to be penetrated. This feeding function is performed simultaneously with the operation of the drill and the fluid for operating the drill and 25 performing the feeding function, is supplied from a common source. The mechanism is provided with a conduit through which the operating fluid enters and in which a hollow shank upon which the body of the tool is 30 mounted telescopes. The conduit is mounted upon a supporting column to have both a longitudinal and swinging adjustment. By virtue of this swinging adjustment, the drill 35 may be so positioned as to drill a considerable number of holes in the breast of the rock without changing the longitudinal position 40 of the mechanism upon the column.

Having briefly outlined my improved construction, I will proceed to describe the same 45 in detail reference being made to the accompanying drawing in which is illustrated an embodiment thereof.

In this drawing, Figure 1 is a longitudinal section taken through the main conduit and 50 the hollow shank which telescopes therein. In this view the drill body connected with the said shank is not illustrated. This view may also be said to be a section taken on the line 1—1 Fig. 3, the fastening bolt for locking 55 the clamping members together, being shown

in a different position. Fig. 2 is an elevation partly in section showing the drill body and a portion of the hollow shank with which it is connected, the latter being shown in section. Fig. 3 is a section taken on the line 3—3 Fig. 60 1. Fig. 4 is a cross section taken on the line 4—4 Fig. 1, the parts being shown on a larger scale. Fig. 5 is a detail view of the two-part ball which is clamped to the conduit in which the hollow shank telescopes. Fig. 6 is an 65 elevation illustrating the manner of operating a tool equipped with my improvements.

The same reference characters indicate the same parts in all the views.

Let the numeral 5 designate the supporting column which may be mounted in the usual manner. To this column is secured a lateral extension 6 to which is clamped a sleeve 7 composed of two parts 8 and 9. Formed integral with the part 9 is a clamping member 10 to which is hinged as shown at 12, the other clamping member 13. Upon a lug 15 of the clamping member 10 is pivotally connected a fastening bolt 14 which when the clamping members are locked in 70 the clamping position, engages a slotted lug 16 formed on the member 13. The clamping members 10 and 13, surround a ball or spherical member 17 composed of two parts 75 clamped to the conduit 18. By virtue of this arrangement there is a universal joint connection between the column 5 and the conduit 18, thus making it practicable to swing this conduit together with its telescoping shank and the drill body, both upwardly 80 and downwardly as well as in a direction 85 passing around the column, within a considerable range of movement.

To what I will term the rear extremity of 90 the conduit 18, is secured a coupling head 19 provided with an inlet port 20 with which a flexible tube 21 may be connected for introducing the actuating fluid. Through an extension 22 of the coupling 19, passes a journal 23 forming a part of a rod 24 whose body 95 portion is angular, preferably cruciform in cross section (see Figs. 3 and 4). To the outer extremity of the journal 23, is secured a holder 25 through which is passed the bar 26 of a hand crank 27. This bar is adjustable in the holder by means of a set bolt 28. Mounted to telescope in the conduit 18 is a 100 hollow shank 29 in whose rearward extremity is inserted a plug 30 whose exterior is slightly cone-shaped to fit the hollow shank 105 110

which is correspondingly fashioned for the purpose. This plug 30 is held in place from the rear by means of a screw plug 31 thread-
ed into the shank and provided with a gasket
5 32 which forms a fluid tight joint between the hollow shank and the main conduit. The plugs 30 and 31 are apertured to receive the rod 24, the openings in the plugs being so shaped that the turning of the rod 24 also ro-
10 tates the shank 29 within the conduit. The construction is also such that the hollow shank is allowed to slide longitudinally on the rod 24 whereby the body of the drill may be forced forwardly when in operation. To
15 the forward extremity of the hollow shank 29 is connected the body of the drill or tool 33, the said body portion having an interiorly threaded socket 34 in which the rear extremity of the shank is threaded. The rear ex-
20 tremity 35 of the drill casing is provided with a port 36 communicating with the hollow conduit, for the purpose of admitting operating fluid to the body of the casing 33 of the tool. This port 36 is controlled by a valve 37.
25 The plugs 30 and 31 are provided with an orifice 38 through which the operating fluid passes from the main conduit 18, into the hollow shank 29 behind the plug 30. Thus when the tool is in operation, the hollow
30 shank 29 is filled with the operating fluid which acts to drive the shank together with the drill body forwardly until the bit 39 en-
gages the breast of the rock or the bottom of the hole in which the drill bit is working.
35 The operating fluid after leaving the port 20, enters a chamber 40 in the rear of the plug 31 and at the same time passes through the orifice 38 into the hollow shank.
The forward extremity of the cruciform
40 rod 24 is provided with a head 24^a in the rear of which is placed a rubber buffer 24^b. This head and buffer form a stop which en-
gage the plug member 30 and limit the for-
ward movement of the shank and drill body
45 whereby the shank is prevented from escap-

ing from the hollow conduit in which it tele-
scopes.

Having thus described my invention, what I claim is:

1. In automatic feed mechanism for per-
cussive tools, the combination of a main fluid conduit, a hollow shank telescoping
50 therein, the rearward extremity of the shank being provided with a plug, means for deliv-
ering operating fluid to the rearward extrem-
ity of the conduit, the plug of the hollow shank being provided with an orifice for the
passage of fluid, a guide rod supported by
55 said plug and passing into the hollow shank
and provided with a stop at its forward ex-
tremity to limit the forward movement of
the shank, a tool casing connected with the
shank, the said casing being in communica-
60 tion with the fluid passing through the hol-
low shank.

2. In apparatus of the class described, the
combination of a hollow conduit, a shank mounted to reciprocate in said conduit, a
65 tool casing connected with the forward ex-
tremity of the shank and movable therewith,
the rear extremity of the shank being pro-
vided with a plug, a guide rod passing
70 through the said plug and provided with a
stop at its forward extremity to limit the
forward movement of the shank and casing, a
75 suitable support for said rod carried by said
conduit, the rear extremity of the rod pro-
truding from the conduit and being jour-
naled in said support, and means connected
80 with the said rod to permit rotation of the
shank and its connections, the rod where it
passes through the plug of the shank being
constructed to cause the shank and rod to ro-
tate in unison.

In testimony whereof I affix my signature 85
in presence of two witnesses.

DANIEL S. WAUGH.
